UNITED STATES PATENT OFFICE.

GEORGE E. WARREN, OF CAMBRIDGE, MASSACHUSETTS.

DESIGN FOR A CONFECTIONERY-TRAY.

SPECIFICATION forming part of Design No. 28,415, dated March 29, 1898.

Application filed February 26, 1898. Serial No. 671,862. Term of patent 7 years.

to all whom it may concern:

Be it known that I, GEORGE E. WARREN, a citizen of the United States, residing at Cambridge, county of Middlesex, and State of Massachusetts, have invented and produced a new and original Design for a Confectionery-tray, of which the following is a specification, reference being had to the accompanying drawing, forming a part thereof.

The drawing shows in perspective a tray illustrating my design.

As shown in the drawing, the leading or material features of my design consist of a base, having a series of stepped ledges $a a' a^2$ in substantially parallel planes one below another and all inclined downwardly toward the front end of the tray, the several ledges being separated from each other by a rearwardly inclined wall a^3 , terminating in a ledge or rib a^4 , projecting slightly above the forward edge of the adjacent ledge, and thereby also having at its extreme forward and lower edge a narrow upturned flange or rib a^5 .

I am aware that trays for this purpose have heretofore been devised in which a suitable base has been provided at its upper side with a series of ledges which were not inclined, but were horizontal, parallel with the bottom of the base, and these ledges were separated by short vertical walls and a series of pocket-like compartments; but such trays are clumsy in appearance and do not present the symmetrical grace and elegance of form and shape which is attained by my design.

I claim—

The design for a confectionery-tray, as herein shown and described.

In testimony whereof I have signed my name to this specification in the presence of two subscribing witnesses.

GEORGE E. WARREN.
